LET BACK CONTROL

John Rinne, Staten Island, N. Y.; Everett H. Ashton, Allston, and Robert G. Mallard, Hopedale, Mass., and Francis Gerard Lake, New York, N. Y., assignors, by mesne assignments, to Steel and Alloy Tank Company, Newark, N. J., a corporation of New Jersey

Original application April 2, 1947, Serial No. 739,004, now Patent No. 2,518,185, dated August 8, 1950. Divided and this application February 3, 1950, Serial No. 142,203

3 Claims. (Cl. 139—313)

1

The present invention relates to a cloth roll take-up mechanism for looms and is a division of application Serial No. 739,004, filed April 2, 1947, now Patent Number 2,518,185.

In the usual automatic type of loom, when the filling is absent by reason of breakage or exhaust of the running supply, the take-up gear transmission is automatically reversed by the tension of the cloth, to effect the desired let-back of said cloth, and thereby prevent the formation of thin streaks in said cloth.

One object of the present invention is to provide new and improved means, effectively controlled and operated to limit the extent of let-back of the take-up roll upon detection of failure of filling, and accessibly mounted for ready inspection, repair or replacements with respect to the take-up gear transmission unit.

The take-up roll is usually mounted in a manner to permit its elevation to be adjusted with respect to the warp line, in accordance with the desired cover of the cloth.

Another object of the present invention is to provide new and improved means for rigidly and firmly mounting the take-up roll in a manner which will permit the elevation of said roll to be easily, quickly and accurately adjusted with respect to the warp line.

Various other objects of the invention will be apparent from the following particular description, and from an inspection of the accompanying drawings, in which:

Fig. 1 is a front view of the left-hand side of a loom embodying the features of the present invention, certain parts of said loom not related to the present invention being absent from the view for the purpose of clarity;

Fig. 2 is a side view of the loom taken approximately along the lines 2—2 of Fig. 1, and showing mainly the gear box for the take-up mechanism and the let-back control mechanism;

Fig. 3 is a section of the loom taken approximately along the lines 3—3 of Fig. 2;

Fig. 4 is a front view of part of the take-up gear box;

Fig. 5 is a section of the take-up mechanism taken approximately along the lines 5—5 of Fig. 4;

Fig. 6 is a section of the take-up mechanism taken along lines 6—6 of Fig. 5;

Fig. 7 is a side view of a section of the take-up gear transmission taken approximately along the lines 7—7 of Fig. 3, and shown with the take-up roll adjusted in its lower position according to the nature of cloth cover desired;

2

Fig. 8 is a section of the loom taken approximately along the lines 8—8 of Fig. 1, but showing mainly the pressure take-up roll structure, the cloth roll structure and the drive input end of the take-up gear transmission near the end of cloth winding operation;

Fig. 9 is a section of the take-up roll structure taken approximately along the lines 9—9 of Fig. 8; and

Fig. 10 is a detail section of the bearing structure at one end of the take-up roll taken on lines 10—10 of Fig. 9.

Referring to the drawings, and especially to Fig. 1, the loom frame may be of the conventional type, but is desirably of the improved form shown in copending application, Serial No. 691,237, filed August 17, 1946, now Patent Number 2,533,128. In this improved type of loom, instead of the conventional loomsides, each with a single frame web, each loomside comprises a pair of parallel webs 10 and 11 rigidly interconnected by suitable girts and bracing members.

Mounted near the front section of the loom is the take-up motion comprising a take-up roll 12 supported on the loomsides in a manner to be more fully described, and covered with sandpaper or similar rough surfaced material adapted to frictionally grip the cloth A after it is formed and advance it towards the cloth roll 13. The cloth roll 13 is pressed into contact with the take-up roll 12 in the manner to be described, and is frictionally driven thereby to wind the cloth around said roll 13.

The take-up roll 12 has secured to the ends thereof gudgeons 14 and 15 (Figs. 1, 9) journaled in suitable bearings on the inside frame webs 10.

One of the gudgeons 14 on the left-hand loomside has secured thereto between the two frame webs 10 and 11 (Fig. 1) a gear 16 by which the take-up roll 12 is continuously driven as the cloth is formed.

The take-up roll gear 16 is driven from the crank shaft of the loom (not shown), which extends parallel to the axis of the take-up roll 12, and which drives through a pair of intermeshing gears (not shown) a short pick cam shaft 17 (Fig. 8), below said crank shaft on the left-hand side of the loom.

On the pick cam shaft 17 is connected a bevel gear 20 meshing with a bevel gear 21 on a drive shaft 22. Between the drive shaft 22 and the take-up roll gear 16, is a take-up gear transmission.

The take-up gear transmission is mounted in a box or casing 25 formed with a peripheral wall 26, extending through an opening 27 in the outer frame web 11. The gear box 25 has a mounting

flange 30 abutting the outer face of the frame web 11 around the web frame opening 27, and is closed at its left-hand side by a plate wall 28 secured to said flange 30 and to said frame web 11 by means of screw studs 31. The plate wall 28 is provided with a flanged opening 33 closed by a removable cover plate 34 supported in position by means of screw studs 35. The cover plate 34 is in readily accessible position and can be removed to permit access to the interior of the gear box 25, as for example, for the purpose of changing the speed ratio according to the desired pick. The cover plate 34 is desirably of transparent material to serve as a window, so that the interior of the gear box 25 can be easily observed.

The gear box 25 is provided with a partition wall 31 serving as a frame support for certain of the bearings of the shafts of the take-up transmission train, and has an outer wall 38 on its right-hand side, serving as a support for the bearings of some of the shafts of the gear train.

On the right-hand side of the gear box 25 is an extension 40 passing through an opening 41 in the inner frame web 10, and having a mounting flange 42 by which said gear box extension is secured to the gear box wall 38 by means of screw studs 43. The drive shaft 22 passes through the rear wall of the gear box extension 40, is journaled in bearings 44 in said rear wall, and carries in the interior of said gear box extension a worm 45 meshing with a worm wheel 46 mounted on a take-up main drive shaft 47. The take-up main drive shaft 47 has one section journaled in bearings 48 in the box walls 31 and 38 respectively and has a section of reduced diameter journaled in bearings 51 in the left-hand box wall 28 and passing through said latter wall to the outside of the gear box 25. The outer end of the reduced shaft section carries a hand wheel 52 for manually taking up or reversing the rotation of the take-up drive.

The take-up gear transmission between the take-up main drive shaft 47 and the take-up roll gear 16 is such as to permit quick and easy changes in speed ratios, in accordance with the picks per inch desired. To that end, the take-up gear transmission comprises a pinion 60 affixed to the take-up main drive shaft 47 between the two gear box plate walls 31 and 38 which drives the gear arrangements enclosed in gear box 25. Said gear arrangements include the drive gear 97 affixed to the projecting part of the countershaft 94 which is supported in bearings 95 and 96 in the walls 31 and 38 respectively. The gear arrangements enclosed in gear box 25 and their mode of operation will not be gone into here as such gear arrangements are not the basis of the claims of this application and are fully described in the parent application Serial No. 739,004, now Patent Number 2,518,185, above referred to. The drive gear 97 meshes with an idler gear 98 which is in mesh with the take-up roll gear 16, and is secured to an idler shaft 99 journaled in a bracket 100. The bracket 100 is supported for rotatable adjustment about the countershaft 94 to maintain the idler gear 98 in mesh with the take-up roll gear 16, irrespective of the elevation of said latter gear.

Means are provided for positively lubricating the gear transmission in the gear box 25, and for that purpose, the drive shaft 22 carrying the take-up worm 45 drives a lubricating oil pump 105 mounted in the gear box extension 40 on the front wall thereof. The lubricating pump 105 is shown of the gear type, and comprises a pair of mesh-

5 ing gears 106, serving as the pumping members, and one of which is fixed to the shaft 22 so as to be driven thereby. The pump 105 has an intake 107 leading from the sump section 107a of the gear box 25, and has an outlet 108 connected to a piping system 109 distributing oil to the different rotating members of the gear transmission. The oil distribution piping system 109 may be of any suitable type, and may have a manifold 110 at its upper end provided with openings for projecting the oil downwardly from the top of the transmission. The oil from this manifold 110 will find its way through the different rotating parts of the transmission and back into the sump 107a.

10 With the construction described, the box enclosed take-up gear transmission will be protected against lint, threads, waste and other foreign substances. Moreover, with this encased construction, lubrication of the gears and bearings is effected efficiently without creating an untidy, oily mess around the loom. Furthermore, the transmission structure being self-contained, it can be mounted or demounted with respect to the loom frame easily and quickly as a unit.

15 The transparent window 34 in the gear box 25 permits observation of the inside of said gear box, so that the condition of the lubricating system in operation can be observed. It is also possible to determine through the transparent window 34 the pick setting of the loom from the position of the pick change gears, and from the number of teeth thereon, which would be marked on the gear.

20 The construction of the present invention is provided with means for driving the take-up mechanism in the reverse direction to the extent required to effect the desired let-back whenever there is an absence of the filling, as a result, for example, of the breakage or exhaust of the running filling supply. To that end, or for the purpose of manually pulling the cloth ahead or back, as is necessary in the initial starting of the loom or positioning the fell of cloth, there is a clutch 111 in the take-up transmission automatically disengaged upon detection of a failure in the filling. The clutch 111 is of the ratchet tooth type, and comprises a clutch element 112 fixed to the take-up worm wheel 46, and meshing with a complementary clutch element 113 feathered on the take-up main drive shaft 47 for slidable movement therealong. The take-up main drive shaft 47 is of a sectional type, and comprises a main hollow section 114 on which the clutch member 113 is splined, and a section 115 journaled in the hollow of the main shaft section 114, and secured at one end to the worm wheel 46.

25 The clutch element 113 is yieldably urged into drive engagement with the clutch element 112 by means of a coil spring 117 embracing the main shaft section 114, and bearing at one end against a shoulder or collar 118 on said shaft section, and at its other end against said clutch element 113.

30 The disengagement of the clutch 111 is effected automatically upon detection of a deficiency in filling by means of a filling feeler slide mechanism 119 which may be of the usual type, and which is operated when the filling breaks, or when the filling is being replenished, to move a rod 120 on the inner side of the inside frame web 10 downwardly. The rod 120 is guided for slid-able movement and urged upwardly in an inoperative position by means of a spring 121 seated on one of the slide sleeve guides 122 affixed to the

inner face of the inside frame web 10, and bearing against a collar 123 secured to said slide rod 120. The slide rod 120 carries a block 124 which engages on its lower side one end of a cam lever 125 pivoted at 126 to the front wall of the gear box extension 40 and which is adapted to engage on its upper side in the upper limiting position of said slide rod a sleeve rod guide 129 affixed to the inner face of the inside frame web 10. The other end of the lever 125 has a cam conformation 127 engaging a cam follower 128 secured to a rock shaft 130 journalled in the front and rear walls of the gear box extension 40, and carrying inside said extension a fork 131 engaging the clutch element 113, and serving to shift said member out of engagement with the clutch element 112 when the slide rod 120 is depressed, either upon filling transfer action, the breakage of the filling, or for manual operation.

The slide rod 120 is automatically operated from the filling slide mechanism 119, or may be manually operated by means of a foot pedal 132 integral or otherwise secured to the collar 123.

Upon the automatic or manual disengagement of the clutch 111 in the manner described, the tension of the cloth A will cause a reverse drive or let-back of the transmission beyond said clutch 111 without interfering with the rotation of the drive shaft 22 and the intermeshing gear members 45 and 46 thereby.

To control the amount of let-back, the part of the drive shaft 47 extending outwardly through the left-hand wall 28, has affixed thereto a ratchet wheel 140 cooperating with a pawl or detent 141 pivotally mounted at 142 to an arm 143 supported on said main shaft 47 for swinging movement thereabout. A spring 145 secured to the arm 143 urges the pawl 141 into engagement with the teeth of the ratchet wheel 140. The lower end of the arm 143 extends into a slot formed between a bracket 146 and the wall 28 to which said bracket is affixed. A series of holes 147 are provided in the bracket 146 for receiving a slack control stud or pin 148.

During normal running operation of the take-up transmission, the ratchet wheel 140 is rotatting clockwise as shown in Fig. 2, so that this ratchet wheel rides idly past the pawl or detent 141. During this rotation, the frictional engagement of the hub of the arm 143 with the drive shaft 47 causes the rotation of said arm, until in limiting position it strikes the end of the bracket 146, as shown in Fig. 2, so that the rotative position of said arm, and in turn, the position of the pawl 141, is predetermined during normal operating conditions. Upon disengagement of the clutch 111, the tension of the cloth causes a reverse rotation of the transmission beyond said clutch, and in turn, causes the ratchet wheel 140 to rotate counterclockwise (Fig. 2). This rotation of the ratchet wheel causes the engagement of said wheel with the pawl 141, and in turn, moves said pawl and the arm 143, until said arm strikes the stud 148 disposed in one of the holes 147, according to the amount of let-back desired. When this arm 143 reaches this limiting position, further reverse rotation of the transmission is stopped.

If it is desired to manually reverse the transmission beyond the clutch 111, this can be easily effected first disengaging clutch 111, lifting pallet 150 and by manipulation of the hand wheel 52 in a counterclockwise direction. The counterclockwise rotation of the hand wheel causes the transmission to rotate in a reverse direction.

The extent of let-back permitted through the hand wheel 52 may be controlled independently of the ratchet and pawl device 140 and 141 by merely moving the pawl 141 out of engagement with the ratchet wheel 140 while said hand wheel is being rotated. To facilitate this manipulation of the pawl 141, said pawl has integral or otherwise rigid thereto a handle extension 150.

As another feature of the present invention, the take-up roll 12 is mounted in bearings in the inside frame webs 10 in such a manner as to permit said roll to be vertically adjusted with respect to the warp line. This elevational adjustment is effected for the purpose well-known in the art. For example, in order to produce cover or a full appearance in the cloth, the take-up roll 12 would be raised, and if the warp is tender, it may be desirable to place said roll in a lower position, to produce less strain on the warp threads.

For roll adjusting purposes, each of the bearings for the gudgeons 14 and 15 of the take-up roll 12 comprises an eccentric bearing housing 160 (Figs. 9 and 10) defining a chamber for an anti-friction bearing unit 161. The bearing housing 160 has a cylindrical section 162 which passes through an opening 163 in the frame web 10 with a snug rotative fit, and which is provided at its outer end with a radially outward flange 164 abutting the outer face of said frame web. The inner end of the bearing housing 160 is closed by a cover 165, which is fastened to said housing by bolts 166, and which has a cylindrical section 167 similar to and abutting the cylindrical section 162 of said bearing housing 160, and a radially outward flange 168. Secured to the inner face of the frame web 10 by welding or the like is a shim plate 170 having a circular opening 171 of the same size as and in registry with the opening 163 in the frame web 10. The shim plate 170 extends around the cylindrical sections 162 and 167 of the bearing housing 160 and its cover 165, and is engaged by the flange 168 on said cover. The opening in bearing housing 160 and its cover 165, through which the gudgeon 14 or 15 extends, is eccentric with respect to the cylindrical sections 162 and 167 of said members, so that upon adjusting rotation of said cylindrical sections in the aligned openings 163 and 171 of the frame web 10 and shim plate 170, the elevation of said gudgeon will be

also changed. It is therefore necessary to move the idler 98 into mesh with the take-up roll gear 16 in its adjusted position. For that purpose, the idler 98 is carried on the adjustable bracket 100 supported on the countershaft 94 of the take-up gear transmission for rotatable adjustment thereabout. The bracket 100 includes two plates 180 and 181 secured together by means of bolts 183 passing through spacer sleeves separating said plates, and is held in adjusted position by means of a clamp 184 bearing against the bracket plate 180 and fastened by a screw stud 185 to the right-hand wall 38 of the gear box 25. By loosening the stud 185, and thereby loosening the bracket 100, said bracket may be rotated to bring the idler gear 98 into mesh with the take-up roll gear 16, irrespective of the elevation thereof.

As many changes can be made in the above apparatus, and many apparently widely different embodiments of this invention can be made without departing from the scope of the claims, it is intended that all matter contained in the above description or shown in the accompanying drawings shall be interpreted as illustrative and not in a limiting sense.

What is claimed is:

1. In a take-up mechanism for a loom, a take-up gear transmission including a take-up main drive shaft, and a drive to said shaft including a clutch disengageable to permit let-back operations under the tension action of the cloth, a casing for said transmission on one side of the loom, said take-up main drive shaft extending in said casing and projecting outwardly through the outer side wall of said casing, and a let-back control device on the outer side of said outer casing wall adjustable to control the extent of cloth let-back and comprising a ratchet wheel on the outward projecting section of said take-up main drive shaft.

2. In a take-up mechanism for a loom, the combination as described in claim 1, in which said clutch is of the unidirectional type automatically disengaged upon rotation of said take-up main drive shaft in let-back direction, said

combination including a handle on the outward projecting section of said take-up main drive shaft manipulable to effect reverse rotation of said latter shaft, said let-back control device being adapted to be manipulated into inoperative position to permit let-back operation through said handle independently of said let-back control device.

3. In a take-up mechanism for a loom, a take-up gear transmission including a take-up main drive shaft and a drive to said shaft including a unidirectional clutch automatically disengaged upon rotation of said drive shaft in let-back direction, and automatically disengaged upon detection of absence of filling to permit let-back operations under the tension action of the cloth, a casing for said transmission on one side of the loom, said drive shaft extending in said casing and projecting outwardly through the outer side wall of said casing, a handle on the outward projecting section of said drive shaft manipulable to effect rotation thereof, and a let-back control device on the outer side of said outer casing wall operating on said drive shaft to control the extent of cloth let-back and manipulable into inoperative position to permit let-back operation through said handle independently of said let-back control device.
